UNITED STATES PATENT OFFICE.

HARRY LUTHER BOESCH, OF WASHINGTON, DISTRICT OF COLUMBIA, ASSIGNOR TO GOVERNMENT OF THE UNITED STATES, REPRESENTED BY THE SECRETARY OF THE NAVY.

TORPEDO.

1,375,821.

Specification of Letters Patent. Patented Apr. 26, 1921.

Application filed December 15, 1919. Serial No. 345,165.

To all whom it may concern:

Be it known that I, HARRY LUTHER BOESCH, a citizen of the United States, residing at Washington, District of Columbia, 5 have invented new and useful Improvements in Torpedoes, of which the following is a specification.

This invention relates to torpedoes and more particularly to improvements in the 10 depth control mechanism.

In order that a clearer perception of the present invention may be had and the objects sought to be accomplished thereby, it may be briefly stated that automobile torpedoes now in use in the Navy are generally 15 launched over the side of a destroyer, for example, and from the height of six to twenty feet and land flat on the water with considerable shock. After launching, the torpedo is maintained at a predetermined 20 depth as desired by means of suitable hydrostatically operated mechanism located on the under side of the central part of the torpedo. The hydrostatic pressure of the water 25 passing through a suitable opening in the torpedo body operates a diaphragm and associated mechanism which in turn controls the angle of the horizontal or depth control 30 rudder in the stern. It is, therefore, one of the objects of the present invention to provide a simple and practical mechanism adapted to take up the shock on the mechanism 35 when striking the water and prevent the shock from being transmitted to the delicately adjusted depth control mechanism.

A further object is to provide a compact mechanism of the above character which may be easily and quickly applied to torpedoes now in use without materially 40 affecting the construction of standard parts.

A further object is to provide a mechanism of the above character which may be inexpensively manufactured and installed 45 and which will be reliable and efficient in use and operation.

Other objects will be in part obvious from the annexed drawings and in part indicated in connection therewith by the following 50 analysis of this invention.

This invention accordingly consists in the features of construction, combination of parts and in the unique relations of the

members and in the relative proportioning and disposition thereof; all as more completely outlined.

To enable others more skilled in the art so fully to comprehend the underlying features thereof that they may embody the same by the numerous modifications in structure 55 and relation contemplated by this invention, drawings depicting a preferred form have been annexed as a part of this disclosure, and in such drawings, like characters of reference denote corresponding parts throughout all of the views, of which:

Figure 1 is a partial sectional plan view of a portion of the torpedo showing the application of the present invention thereto.

Fig. 2 is a vertical sectional view of a portion of the torpedo and

Fig. 3 is a sectional view substantially at right angles to the parts shown in Fig. 2.

Referring now to the drawings, a member 5 is in a ring 6 adapted to be carried by a 75 part 7 which is bodily placed or secured on the under side of the central part of the torpedo body. This member 5 is provided with an opening 7', Fig. 2, communicating with the exterior of the torpedo whereby 80 the water is permitted to act directly upon a diaphragm 8, the motion of which is transmitted through the stem 10 and yoke 11 pivoted at the point 12 at one side and connected with a rod 13 at the opposite side 85 leading to the depth control mechanism as indicated. This diaphragm is normally held in predetermined position by means of two compression springs 14 located in suitable 90 pockets 15, the compression of which may be adjusted in any desired well-known manner. These springs before launching normally exert a downward pressure upon the diaphragm 8 consequently holding the rod 13 in a relatively lower position until after the 95 torpedo is launched. However, the hydrostatic pressure on the under side of the diaphragm counter-balances the expansion of the springs consequently returning the rod 13 to its relative normal position. Any 100 fluctuation in the depth of the torpedo will cause a corresponding variation or difference between the expansion of the springs 14 and the hydrostatic pressure, which variation will result in a movement of the rod 13 to 105 produce the desired effect upon the depth

control mechanism to restore the torpedo to its proper depth below the surface of the water. This mechanism for the most part is of standard construction and the present 5 invention is directed more particularly to the insertion of a shock absorber between the diaphragm and the depth control mechanism adapted to take up the severe shock or strain occurring at the moment of launching 10 and prevent the shock from being transmitted through to the depth control mechanism.

By referring to Fig. 3 it will be noted 15 that a member 15' is adapted to support the ends of the compression springs and this member is pivoted at 16 to the stem 10 and provided at its lower end with a screw threaded nut 17 supporting a spring 18 coiled about the stem, Fig. 3. A bearing 20 member 21 is provided with an inwardly projecting flange 20 at its upper part which forms with the stem and nut 17 a chamber for the spring 18 and an abutment for the opposite end. The bearing member 21 is 25 trunnioned at 22 to the opposite sides of the yoke 11. It will thus be seen that when the torpedo is launched the water entering through the opening 7' is free to move 30 the diaphragm 8 upwardly against the action of the compression springs 14 but by reason of the interposed spring 18 a shock will not be transmitted to the depth control rod 13 as the threaded nut 17 will be free to slide upwardly into the chamber 35 formed by the bearing member 21 housing the compression spring 18.

It is thus seen that the present invention provides a simple and practical construction adapted to take up the shock on launching 40 the torpedo and prevent the same from being transmitted as above described.

The invention may be readily applied to 45 torpedoes now in general use without materially affecting the other parts and at a minimum of expense and trouble.

It is believed that the construction, method of use and operation of mechanism of this character will be clear to those skilled in the art and a further description 50 is, therefore, believed to be unnecessary.

Without further analysis, the foregoing will so fully reveal the gist of this invention that others can by applying current knowl-

edge readily adapt it for various applications without omitting certain features that, 55 from the standpoint of the prior art, fairly constitute essential characteristics of the generic or specific aspects of this invention, and, therefore, such adaptations should be and are intended to be comprehended within 60 the meaning and range of equivalency of the following claims:—

What I claim is:—

1. In a torpedo, in combination, depth 65 control mechanism, a diaphragm exposed to hydrostatic pressure, and a shock absorber interposed between the diaphragm and the depth control mechanism adapted to take up the shock when launching the torpedo.

2. In a torpedo, in combination, depth 70 control mechanism, a diaphragm exposed to hydrostatic pressure and a shock absorber interposed between the diaphragm and the depth control mechanism adapted to take up the shock when launching the torpedo, said 75 mechanism including a pivoted member directly connected with the depth control mechanism and two relatively movable members interposed between the diaphragm and said pivoted member.

3. In a torpedo, in combination, depth 80 control mechanism, a diaphragm exposed to hydrostatic pressure, and a shock absorber interposed between the diaphragm and the depth control mechanism adapted to take up the shock when launching the torpedo, said mechanism including a pivoted member directly connected with the depth control mechanism and two movable members interposed between the diaphragm 90 and said pivoted member and yielding means adapted normally to hold said movable members in normal position.

4. In a torpedo, in combination, a depth 95 control mechanism, a diaphragm open to hydrostatic pressure and shock absorbing means interposed therebetween, said means including a lever adapted to be normally actuated on fluctuations of the diaphragm to transmit motion to the depth control 100 mechanism, and spring retained members telescoping one with another and interposed between the diaphragm and the lever.

Signed at Washington, District of Columbia, this 21st day of July, 1919.

HARRY LUTHER BOESCH.
